UNITED STATES PATENT OFFICE.

HARRY BENTZ, OF MONTCLAIR, NEW JERSEY.

AIR-CONDITIONING APPARATUS.

1,218,045.

Specification of Letters Patent. Patented Mar. 6, 1917.

Application filed September 4, 1914. Serial No. 860,166.

To all whom it may concern:

Be it known that I, HARRY BENTZ, a citizen of the United States, residing in Montclair, Essex county, New Jersey, have invented certain new and useful Improvements in Air-Conditioning Apparatus, of which the following is a specification.

In apparatus for washing air and gases or for humidifying or "conditioning" the air, as it is commonly called, the air is passed through or over water, cooled or warmed or at ordinary temperatures according to the desired results.

My present invention provides certain improvements in this class of apparatus, and especially in air cooling apparatus whereby a considerable economy is effected and the apparatus is brought to a very high state of efficiency.

20 The accompanying drawings illustrate embodiments of the invention.

Figures 1 and 2 are respectively a longitudinal section and a plan of an air cooling or humidifying apparatus;

25 Fig. 3 is a plan of a similar apparatus designed chiefly for cooling the air.

Referring to the embodiments of the invention illustrated a closed casing A of sheet metal, connected at one end to the air supply and at the other end to a fan or other means for drawing the air through, is mounted on a concrete base B; and is provided with successive groups of sheds C, C', C'', each shed comprising a vertical column 30 of plates, approximately L-shaped in cross section, obliquely arranged and extending transversely across the chamber with narrow horizontal spaces between them, and tanks D, D', D'' overhead are provided with 35 perforated bottoms through which a considerable volume of water flows so as to provide a continuous film of water flowing down the forward faces of the several sheds. This type of apparatus is described and 40 illustrated more fully in my application No. 843,185, filed June 5, 1914. Each group of sheds is supported on cross beams E which in turn are supported on longitudinal beams F, the lower ends of the several sheds being 45 immersed in water accumulated in the separate sumps G, G', G'' so that the air cannot pass below the sheds, but must pass through them and over their wet faces.

The supply pipe H for the water may be 50 connected with an artesian well or with other source of naturally or artificially

cooled water which passes therefrom by way of a branch J into the upper tank D at a rate regulated by a valve K. From this tank the water runs down over the first group of sheds C and into the sump G. Connected to this sump is the inlet pipe L of a pump M which lifts the water through a vertical pipe N into an extension O of the supply pipe which is cut off from the branch J by an intermediate valve P normally closed. From the pipe O a branch Q discharges the water into the second overhead tank D' whence it runs down over the group of sheds C' into the second sump G'. This sump is connected with the inlet pipe R of a pump S which lifts the water through a vertical pipe T into an extension U of the supply pipes H and O, which is cut off by a valve V from the branch Q and which has a branch W discharging into the third overhead tank D''. Thence the water flows over the third group of sheds C'' into the sump G'' and away to the waste. The inlet pipes L and R of the pumps communicate with the sumps G and G' at points above the level of the bottoms of the contact plates, so as to insure that the water shall always stand above the bottoms of such plates.

The air entering through the admission end X of the casing and escaping through the discharge end Y is first brought into contact with the sheds C' then with the sheds C' and finally with the sheds C. The warmest air is brought into contact with the water which has been previously used in the two sheds C and C' and which has consequently been considerably warmed by contact with the air. The air striking the sheds C' has been somewhat cooled by passage through the sheds C' and comes into contact with water which has been only slightly warmed by its previous passage over the first set of sheds C. Finally the air striking the sheds C has been successively cooled by the passage through the sheds C' and C' and comes into contact with the water in its coldest condition. Thus by the counter-current arrangement of the air and water through the apparatus the warmest water is used for the reduction of the temperature of the air in its warmest condition and as the air becomes cooler the water with which it comes into contact also is cooler and the apparatus works with the highest efficiency. For example, if the water supply in the first tank is at 52° Fahrenheit that in the second tank

may be 56° and that in the third tank 60°. Air entering at about 90° will be reduced by the first sheds to about 75°, by the second sheds to about 65° and in the third sheds to about 58°. At the same time the quantity of the water drawn through the supply pipe is only that which is sufficient to wet the first group of sheds C, though the quantity actually in use is a multiple thereof (two or three or more times the volume drawn through the supply pipe, according to the design of the apparatus). The only extra expense involved in this economy of water is that required in the operation of the pumps M and S. But as these have to lift the water only from the bottom to the top of the apparatus the operation is more economical than if the extra volume in use had to be lifted from a substantial depth in an artesian or other well.

The casing A incloses a single air-chamber which is of uniform cross-section throughout substantially its entire length. The transverse contact plates in each stage form restricted passages for the air. The successive stages C, C' and C² are separated from one another by comparatively wide spaces. These spaces, being of the full cross-section of the chamber, cause a reduction in the velocity of the air. Thus the velocity of the air is alternately increased in passing through a stage of plates and checked in passing from one stage to the next, and this checking of its velocity causes a precipitation of the moisture which was carried along merely by the velocity of the current, and the air is thus rendered more susceptible to the cooling effect of the cooler water on the next stage of plates. The use of a plurality of columns or sheds in each stage makes it possible to get from the water in each stage the maximum cooling effect which can be efficiently gotten. Where the difference in temperature between the air and the water is 30°, for example, at the entrance to a stage the successive cooling operations as it passes from one shed to the next will reduce the temperature of the air half this amount, or 15°. At this reduced temperature the volume of water which can be carried by the air is reduced and the reduction in velocity takes place which permits a substantial precipitation between the successive stages of plates; thus again rendering the air current more susceptible to the cooling action of the water in the next stage.

In the vertical pipes N and T extending upward from the pumps there are provided valves Z and α . By shutting off these valves and opening the valves K, P and V in the upper line of piping the supply from the main pipe H may be directed immediately into all the tanks D, D', D². Or by closing the valves V and Z, leaving the first pump M idle, the water may be directed from the

main H into the two tanks D and D' and reused only in the tank D². Or by closing only the valves P and α (stopping the pump S) the water may be used in the first stage only in the first tank D and lifted by the pump N for a second use simultaneously in the two tanks D' and D². The pipes and valves, therefore, admit of a use of the apparatus in various ways.

Where it is desired to impart moisture to the air the water may be heated for greater efficiency in this respect as by means of a heater b (Fig. 2). In this case the water coming in through the pipe H may be heated to a high temperature. Its temperature is somewhat reduced in the sheds C. The pump M is operated to lift it out of the sump G as before; but, the valve Z being closed and the valve α leading to the heater being open the water will pass through the pipe d into the heater b and up through the heater which will restore the heat extracted in the sheds C. The water thence passes by a pipe e out of the upper end of the heater into the overhead pipe O and thence into the overhead tank D'; or, the valve V being open and the valve α closed, into both tanks D' and D² simultaneously. Or the water from only the second sump G' may be reheated. In this operation the valve α in the pipe leading upward from the pump S will be closed, the valve f open and the valve c closed. Or the water from both sumps G and G' may be simultaneously reheated by opening both the valves c and f and closing the valves Z and α . The system of piping illustrated, therefore, with its valves permits of using the apparatus in a great variety of ways according to circumstances and the desired ends.

In the arrangement shown in Fig. 3 the overhead tanks are increased in number, only four being shown within the limits of the drawing. This figure shows also an alternative arrangement of the piping. The main pipe H leads directly to the second tank D'. The water from this tank after passing over the sheds and into the sump is raised by means of a pump M having an inlet pipe L and an upwardly extending pipe N which communicates with an overhead pipe O constituting an extension of the main supply pipe; which in turn has a branch Q discharging into the next overhead tank D² whence the water is run over the sheds and into the sump and raised through the pipe R, pump S and pipe T into an overhead pipe U discharging through the branch W into the next overhead tank. The first tank D, however, is supplied with especially cold water for effecting the final cooling operation and for this purpose a cooler g in which the water may be brought to approximately freezing temperature has an outlet pipe h leading upward and through

a lateral extension *j* discharging into the first overhead tank *D*. The water then passes down over the corresponding sheds and into the sump whence it is drawn by the 5 inlet *k* of a pump *l* which forces it through a pipe *m* into the upper end of the cooler. It is thus circulated continuously in a short 10 circuit arranged expressly for the series of sheds which produces the final cooling effect. The cooler *g* as well as the heater *b* may be 15 of any usual or suitable types. For example, the water in the cooler *g* may be cooled by means of ice or cold brine passing through internal coils; and the water in the heater *b* may be heated by a steam coil.

Though I have described with great particularity of detail certain embodiments of my invention, yet it is not to be understood 20 therefrom that the invention is restricted to the particular embodiments disclosed. Various modifications thereof in detail and in the arrangement and combination of the parts may be made by those skilled in the art without departure from the invention.

25 What I claim is—

1. An air-conditioning apparatus including in combination a casing inclosing a single air chamber of uniform cross-section throughout substantially its entire length, 30 means for passing a current of air horizontally therethrough, transverse contact plates arranged in a plurality of successive stages in said single chamber in the path of the air and means for flowing a body of water over said stages of plates in succession and in the reverse order of that in which they are engaged by the air current.

2. An air-conditioning apparatus including in combination a casing inclosing a single air chamber of uniform cross-section throughout substantially its entire length, 40 means for passing a current of air horizontally therethrough, transverse contact plates arranged in a plurality of successive stages in said single chamber in the path of the air and means for flowing a body of water over said stages of plates in succession and in the reverse order of that in which they are engaged by the air current.

the air and means for flowing a body of water over said stages of plates in succession and in the reverse order of that in which they are engaged by the air current, the 50 plates in each stage forming restricted passages for the air and the successive stages being separated from each other by a comparatively wide space, so that the velocity of the air is alternately increased in passing through a stage of plates and checked in 55 passing from one stage to the next to precipitate free moisture therefrom.

3. An air-conditioning apparatus including in combination a casing inclosing a single air chamber of uniform cross-section 60 throughout substantially its entire length, means for passing a current of air horizontally therethrough, transverse contact plates arranged in a plurality of successive stages in said single chamber in the path of the air and means for flowing a body of water over 65 said stages of plates in succession and in the reverse order of that in which they are engaged by the air current, each stage of plates consisting of a group of sheds close together 70 and each shed comprising a vertical column of plates with narrow spaces between them, so that the air is subjected a number of times to the same water in passing through each stage of plates and is brought as nearly as 75 practicable to the temperature of such water, the successive stages being separated from each other by a comparatively wide space, so that the velocity of the air is alternately increased in passing through a stage of plates 80 and checked in passing from one stage to the next to precipitate free moisture therefrom.

In witness whereof, I have hereunto signed my name in the presence of two subscribing witnesses.

HARRY BENTZ.
